UNITED STATES PATENT OFFICE.

JAMES R. DENISON, OF TACOMA, WASHINGTON.

EXTRA DECK.

1,052,221.

Specification of Letters Patent.

Patented Feb. 4, 1913.

Application filed February 25, 1909, Serial No. 480,014. Renewed January 2, 1913. Serial No. 739,924.

To all whom it may concern:

Be it known that I, JAMES R. DENISON, a citizen of the United States, residing at Tacoma, in the county of Pierce and State 5 of Washington, have invented a new and useful Extra Deck, of which the following is a specification.

My invention relates to extra decks for ferry-boats, and the like, where it is necessary to have a supplemental deck, which 10 may be adjusted to different elevations, to accommodate wharves of varying heights; to meet the changes of water-level due to movements of the tide; and also, where it is 15 desired to transfer a cargo from one boat to another, the decks of the two boats having to be adjusted to the same level.

One of the objects of my improvement is to provide a boat with a deck of the character 20 mentioned, provided with a novel form of superstructure, to withstand, efficiently, the strains incident to its operation.

A further object is the provision of new and improved operating means for raising 25 and lowering the deck, so as to maintain, readily, a quick but full control over its movement.

Still another object which I accomplish by this invention, is an easy up and down movement of the adjustable deck, and this I attain by the peculiar form of supporting guides, hereinafter described.

An additional object is the provision of a novel arrangement of connecting gears for 35 operating the extra deck, so that the same engine which is used to propel the boat, may be employed for moving the deck, and in a ready and expeditious manner.

Further objects and advantages will appear 40 from the following detailed description, and the appended claim wherein the invention is pointed out more precisely.

In the accompanying drawings, forming a part of this specification, and which are to 45 be read in conjunction therewith, Figure I is a top plan view, with parts broken away, of a boat equipped with my improvements, and Fig. II is a vertical, sectional view of the same, also showing cars positioned on 50 the adjustable deck.

Referring more particularly to the drawings, in which like letters of reference indicate corresponding parts in the different views, A' designates the deck of the boat, and A² the extra deck, adjustable up and 55 down, to accommodate wharves of different

heights, when the boat may be higher or lower, owing to tidal changes; or loading from one boat to another, and other similar purposes, where vertical relative adjustment 60 between the delivering and receiving platforms is required.

Fixedly secured to the deck A² are the threaded boxes b', which may be of any suitable number, according to the size of the 65 boat, and the deck to be adjusted. At the outer ends of the boxes b' are T-shaped openings, arranged to engage the vertical T-shaped guide-posts b², which are secured to the deck A' in any convenient manner. 70

Positioned in the bottom of the boat are the pedestals b³, in which are rotatably mounted the threaded posts b⁴, the same being arranged to engage and move through the boxes b'. 75

b⁵ are gears keyed to the posts b⁴ at their lower ends. Positioned to engage the gears b⁵ are worm-wheels b⁶, which are mounted rigidly on the shafts b⁷, running longitudinally of the boat. There are four such 80 shafts b⁷, each carrying a miter-pinion b⁸ at its inner end.

Arranged transversely of the boat is the main power shaft b⁹, carrying the miter-gears b¹⁰, adapted to mesh with the afore- 85 mentioned miter-pinnions b⁸.

b¹¹ is a clutch for controlling the movement of the shafts b⁷ from the power shaft b⁹, and b¹² is a lever for operating the clutch b¹¹. 90

The guide-posts b² are braced by the longitudinal beams b¹³. b¹⁴ are cross-braces, serving, additionally, to strengthen the guide-posts b², and maintain the entire structure rigid. b¹⁵ are side-braces, secured to 95 the deck A', and extending to the guide-posts b². Arranged at the top of the guide-posts b², are the transverse beams b¹⁶. In this manner, I provide a completely rigid framework, or superstructure, properly braced at 100 every point, and which serves, effectually, to support the extra deck, at any elevation, and with any weight.

b¹⁷ are tie beams, connecting each pair of 105 oppositely positioned boxes b'.

The extra deck, I have shown, here, as provided with tracks b¹⁸, C, indicating cars positioned thereon, but it is to be understood that the tracks may be omitted, and the deck made perfectly plain, or in any other form 110 desired, to suit the particular purposes.

Various other changes that may be made,

without departing in any sense from the spirit of my invention, and any such modifications are to be comprehended by the claim hereto appended.

5 What I claim, and desire to secure by Letters-Patent, is:—

In combination with the body-portion of a boat, of a movable deck, of threaded posts rotatably mounted on said body-portion, **T**-shaped guide-posts also mounted on the body-portion, longitudinal and lateral braces for holding said guide-posts against either longitudinal or lateral movement, relative to the body-portion of the boat, boxes carried by the movable deck, and provided with **T**-shaped openings by which they are adapted to fit closely and move vertically

on the afore-mentioned guide-posts, said boxes being further provided with threaded openings engaging the aforementioned threaded posts, pinions mounted on the said threaded posts, shafts arranged longitudinally of the boat, worms on said shafts and in engagement with the pinions, a power shaft arranged transversely and centrally of the boat and in engagement with the longitudinal shafts beforementioned, and a clutch-mechanism controlling said transverse shaft.

JAMES R. DENISON.
